ROBERT S. PORTER, OF SAN DIEGO, CALIFORNIA, ASSIGNOR OF ONE-HALF TO HOWELL
A. WILLIAMS, OF SAN DIEGO, CALIFORNIA.

AUTOMATIC FLASH-LIGHT FOR ELEVATOR-THRESHOLDS.

1,361,743.

Specification of Letters Patent.

Patented Dec. 7, 1920.

Application filed December 19, 1917. Serial No. 207,989.

To all whom it may concern:

Be it known that I, ROBERT S. PORTER, a citizen of the United States, residing at San Diego, in the county of San Diego and 5 State of California, have invented a new and useful Automatic Flash-Light for Elevator-Thresholds, of which the following is a specification.

This invention has reference to automatic 10 flash-lights for elevator thresholds, and its object is to provide a lighting means for elevator thresholds which shall be operated to illuminate the threshold when an elevator comes to rest at a landing.

15 The thresholds at elevator landings are often obscured, making it difficult for passengers to clearly see the threshold, and annoyance and often accidents occur. In order to avoid this difficulty, the invention 20 provides a light which is caused to shine only when the elevator comes to a standstill, the energization of the lamp being under the control of the elevator operating devices.

25 The invention comprises electromagnetic means rendered active by the movement of the elevator controller, causing the elevator to travel, to open the electric circuit of the lamp, and when the elevator is brought to a 30 standstill the circuit of the electromagnetic devices is broken, whereupon the lamp circuit is automatically closed, and the lamp glows until the elevator is again started, the lamp being properly placed to illuminate 35 the threshold and thus guide passengers through the elevator door.

The same structure is susceptible of being 40 operated in the reverse order, that is, the lamp is caused to be illuminated when the electromagnetic means is energized. In this way, the invention may be utilized for other purposes than illuminating the thresholds of elevators, for it may be employed as a signal device to be active only when some structure 45 is also active.

The invention will be best understood from a consideration of the following detailed description, taken in connection with the accompanying drawings forming part of 50 this specification, with the further understanding that, while the drawings show a practical form of the invention, the latter is not confined to any strict conformity with the showing of the drawings but may be

changed and modified so long as such 55 changes and modifications come within the scope of the appended claims.

In the drawings:

Figure 1 is a sectional view of an elevator cage with the invention applied, and indicating rays illuminating the threshold;

Fig. 2 is a vertical section through the casing containing electromagnetic switch controlling means;

Fig. 3 is an elevation with some parts 65 broken away of the right hand end of the structure shown in Fig. 2;

Fig. 4 is a section of a portion of a structure like that of Fig. 2, but showing a somewhat modified construction.

Referring to the drawings, there is shown an elevator cage 1 with a controller 2 therein, which may be taken as indicative of an ordinary controller, whereby the travel of the cage is regulated. Close to the 75 threshold 3 of the elevator there is mounted an electric lamp 4, which may be shaded by a casing 5, so as to throw illuminating rays 6 upon the threshold under circumstances to be described.

At some convenient point, say, under the bottom of the elevator cage, is a casing 7, which may be a metal casing, having one side 8 removable for access to the interior. By forming the casing 7 of metal, it is protective of parts inclosed therein, but it is to be understood that the casing may be made of other materials than metal.

Within the casing there is mounted an 90 electromagnet 9 of any suitable type, this magnet being usually suspended with a polar extremity 10 lowermost. Terminals 11 of the magnet are connected to binding posts 12 extending through and insulating from the casing and exterior thereto receiving conductors 13, one of which may lead into the controller 2 and the other connected up in a suitable power circuit. The arrangement is such that when the controller 2 is in position to cause the elevator to 100 move, the circuit through the conductors 13 is closed, but when the controller 2 is brought to the open position, that is, where the elevator is caused to stand still, the circuit through the magnet is opened, and consequently the magnet is deenergized.

The lamp 4 is provided with conductors 14 and 15 respectively, the conductor 14

leading to the casing 7 to which it may be electrically connected by a binding post 16, so that the casing 7 may constitute a part of the circuit. The conductor 15 is assumed 5 to be carried to a suitable source of current.

The magnet 9 is provided with an armature arm 17 having a pivot connection 18 with a side of the casing 7. The arm 17 10 carries an armature 19 in position to be attracted by the polar extension 10, while the free end of the arm has a contact 20 in its path, this contact having a binding post extension 21 projecting through the casing, 15 but insulated therefrom. A conductor 22 is connected to the extension 21, and is assumed to be carried to a suitable source of current.

In Fig. 4, there is provided another contact 23 in the path of the arm 17 on the side 20 thereof remote from the contact 20. The contact 23 is carried by a contact 24 fast to the casing 7, with the contact 23 insulated from the bracket, so that the contact may be connected up in circuit if desired.

25 In the structure shown in Figs. 1, 2 and 3, the magnet 9 is energized so long as the elevator is running either up or down. Under these circumstances, the lamp circuit is broken, and of course the lamp is dark.

30 When the elevator comes to rest at a landing, the controller 2 is moved to the off position, and in this position, the circuit through the magnet 9 is broken, wherefore the armature 19 is no longer attracted, and the arm 17 moving about its pivot 18 falls by gravity onto the contact 20, thus completing the circuit through the conductor 14, casing 7, arm 17 and contact 20 to the conductor 22, whereupon the lamp 4 glows and illuminates 35 the threshold 3, permitting passengers to readily see their way into and out of the elevator. As soon as the elevator again starts to travel, the magnet is energized, the armature is attracted, and the lamp circuit 40 is broken, so that the lamp again becomes dark. Sometimes it is desirable to cause a signal when the moving parts are in action, as, for instance, to show that a motor or some other machine is running. Under

45 such circumstances, the structure represented by and contained within the box 7 may be arranged as shown in Fig. 4, so that the energization of the magnet will close 50

the lamp circuit and cause the lamp to glow so long as the magnet circuit is closed. 55

What is claimed is:

1. The combination with an elevator cage having an electric controller thereon for the cage, of an electric lamp on and movable with the cage and positioned to illuminate the threshold of the elevator, an electro-magnet on the cage in circuit with the controlling means for the cage for energization each time the controller circuit is closed, a gravity switch in the lamp circuit under 60 the control of the electro-magnet and including a circuit terminal in the lamp circuit, and another circuit terminal in the path of the first-named circuit terminal in the lamp circuit, whereby, when the elevator is running, the switch is maintained in the open position by the energization of the electro-magnet and when the elevator stops at a landing the electro-magnet is deenergized and the switch falls to closed position. 75

2. The combination with an elevator cage provided with an electric controller for operating the cage, of an electric lamp on the cage and positioned to illuminate the threshold thereof, and an electro-magnetic switch for the lamp circuit carried by the elevator cage and included in the operating circuit of the elevator cage, said switch comprising an electro-magnet, an armature therefor, circuit terminals for the lamp circuit, one carried by the armature and the other in the path of the first-named terminal, and a closed box inclosing the electro-magnet, armature and circuit terminals and carried by the elevator cage, whereby the starting of the elevator cage causes the energization of the magnet and the opening of the lamp circuit and the stopping of the cage causing the closing of the lamp circuit by the drop of the armature under the action of gravity, and the magnet, armature and contacts are protected from harm and contamination. 85

In testimony that I claim the foregoing as my own, I have hereto affixed my signature 90 in the presence of two witnesses.

ROBERT S. PORTER.
